J. H. EASTMAN

CIGAR LIGHTER

Filed Feb. 15, 1922

6-16 Inventor
James H. Eastman.

By *Stuart C Barnes*

Attorney

UNITED STATES PATENT OFFICE.

JAMES H. EASTMAN, OF DETROIT, MICHIGAN.

CIGAR LIGHTER.

Application filed February 15, 1922. Serial No. 536,640.

To all whom it may concern:

Be it known that I, JAMES H. EASTMAN, a citizen of the United States, residing at Detroit, in the county of Wayne and State 5 of Michigan, have invented certain new and useful Improvements in Cigar Lighters, of which the following is a specification.

This invention relates to cigar lighters and especially to a combined cigar lighter 10 and advertising device. It has for its object a cigar lighter which uses a discharge of harmless electric sparks to ignite the cigar. At the same time this discharge takes place an electric light flashes and draws attention 15 to advertising matter.

In the drawings,—

Fig. 1 is a perspective of the device, with parts broken away.

Fig. 2 is a diagrammatic view of the wir- 20 ing.

a designates a case which, of course, can be of any description. Within this case is located an electric lamp *b* behind a glass *c*, on which is inscribed an advertising legend. 25 This glass is in the front of the case directly before whoever desires to use the cigar lighter. The cigar lighter comprises a pair of terminals *d* which have their outer ends turned down so that they can be used to 30 light a pipe as well as a cigar. These terminals are spaced apart some distance as shown in the drawing.

It is the object of the present invention to provide a discharge of sparks generated by a 35 high frequency and high voltage current. Such a current is harmless if the person using the igniter accidentally gets a shock, as the same character of current is used in electrotherapeutic apparatus. At the same 40 time the arc formed by this current will leap a very considerable gap and will ignite anything combustible that is held in its path.

The wall plug is designated *f*. The primary circuit is designated *e* and extends 45 from the wall plug through the switch *g*, is coiled about the magnet core *h* and then passes to the primary winding *i* of the induction coil, thence back to the vibrator screw *j*, across the interrupter gap *k* to the 50 armature *m* and back to the wall plug.

In parallel with this circuit is the incandescent lamp *b*. A condenser *n* is bridged across the interrupter gap *k*, hence when the push button switch *g* is closed, the cur-

rent from the ordinary 110 volt circuit 55 passes around the magnet core *h*, attracting the armature *m*, and consequently breaking the circuit and causing a continuous vibration by this make and break. This making and breaking of the current builds up the 60 electrical charges in the condenser and when the circuit is open the current surges across the interrupter gap, producing an oscillating current of very high frequency passing through the primary winding *i* of the induction coil. This is transformed into a high 65 frequency, high voltage current by the secondary winding *p* of the induction coil.

The two terminals *d*, *d* afford a gap in this secondary circuit through which this 70 high frequency, high voltage current will leap by reason of its high potential, anywhere from 50,000 to 75,000 volts if the windings are given the appropriate number of turns. The frequency of a current of 75 this character is enormous; in fact, probably anywhere from 100,000 to 1,000,000 per second.

This arrangement provides a hot but 80 harmless spark. It can be used as a direct igniting means when coupled up with an ordinary lighting circuit. At the same time the push button switch *g* can be utilized to light the incandescent bulb filament. Hence the same switch coincidentally 85 illuminates the advertising sign and turns on the spark by which the person addressing the case may ignite his cigar, cigarette or pipe.

What I claim is:

In a cigar lighter, the combination of a support, a pair of electrical terminals supported upon the same in spaced relation to permit the exposure of a cigar to the line of sparks passing continuously from terminal to terminal, means within the support for transforming an ordinary lighting circuit current into a relatively very high potential, high frequency current, and means for conducting said current to the 100 terminals, said two last mentioned means including a switch remote from the terminal which may be held closed to cause a continuous line of sparks to pass between the terminals and ignite the cigar. 105

In testimony whereof I affix my signature.

JAMES H. EASTMAN.
